(57) **CLAIM**

The ornamental design for the ceramic tile levelling device, as shown and described.

DESCRIPTION

FIG. 1 is a perspective top view of a ceramic tile leveling device showing the new design;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.

Subject matter shown in broken lines, is shown for the purpose of illustrating environmental structure and does not form part of the design claimed. The Applicant reserves the right to claim any combination or subset of the subject matter, whether shown in broken lines or solid lines, in one or more amendments to this application.

Subject matter shown in solid lines illustrates the claim design.
